CLAIM

The ornamental design for an earbud, as shown and described.

DESCRIPTION

FIG. 1 is an oblique view of an earbud showing the new design;

FIG. 2 is a front view of the earbud of FIG. 1.

FIG. 3 is a rear view of the earbud of FIG. 1.

FIG. 4 is a right view of the earbud of FIG. 1.

FIG. 5 is a left view of the earbud of FIG. 1.

FIG. 6 is a top view of the earbud of FIG. 1.

FIG. 7 is a bottom view of the earbud of FIG. 1.

FIG. 8 is an exploded view of the earbud of FIG. 1; and, FIG. 9 is an alternative exploded view of the earbud of FIG. 1.

The appearance of any portions of the article between the disassembled or exploded portion of the earbud form no part of the claimed design.

1 Claim, 9 Drawing Sheets
